UNITED STATES PATENT OFFICE.

CHARLES W. DAKE AND CRAWFORD P. McGINNIS, OF CHICAGO, ILLINOIS, ASSIGNEES
TO PYLE-NATIONAL ELECTRIC HEADLIGHT COMPANY, OF CHICAGO, ILLINOIS, A
CORPORATION OF NEW JERSEY.

RECORDED.

1,104,250.

Specification of Letters Patent.

Patented July 21, 1914.

Application filed April 25, 1913. Serial No. 763,497.

To all whom it may concern:

Be it known that we, CHARLES W. DAKE and CRAWFORD P. McGINNIS, citizens of the United States, residing at Chicago, in the 5 county of Cook and State of Illinois, have invented a certain new and useful Improvement in Recorders, of which the following is a specification.

Our invention relates to improvements in 10 indicators and has for one object to indicate violent changes in the velocity of moving vehicles or other moving parts. It is so arranged that it is in operation and indications are made only when sufficiently violent 15 changes are to be recorded. Thus the life of the blank record sheet or member is extremely long, since instead of moving in response to any fixed driving means it operates only when it is necessary for it to operate to get a record and the device thus needs 20 a minimum of attention.

It is illustrated diagrammatically in one form in the accompanying drawings, where-
in—

25 Figure 1 is a side elevation in part section with parts broken away; Fig. 2 is a plan view in part section with parts broken away; Fig. 3 is a front elevation in part section with parts broken away; Fig. 4 is a side 30 elevation with parts broken away somewhat along the line 4—4 of Fig. 2; Fig. 5 is a plan view of one of the recording pendulums with parts in section; Fig. 6 is a section along line 6—6 of Fig. 3; and Fig. 7 is a 35 plan view of the record sheet.

Like parts are indicated by the same letter in all of the figures.

A is a base upon which is mounted a cover A¹ held in position by the lugs A² and 40 the lock A³ and provided with a transparent window A⁴.

B is a bracket mounted on the base A supporting the record drum B¹ rotatably mounted thereon.

45 B² is a tooth ratchet wheel keyed to the drum.

B³ is an arm pivotally mounted on the bracket B provided with the tooth B⁴ in engagement with the tooth ratchet wheel B¹ and held against the ratchet wheel by the 50 spring B⁵.

C is a bracket.

C¹ is a roller rotatably mounted thereon.

C² is a record sheet wound about the roller

and extending over and wound about the 55 drum B¹.

C³ is a shaft upon which the roller C¹ is mounted.

C⁴ is a spring disposed between the hub of the sleeve C⁶ on the bracket C and the 60 portion of the roller to yieldingly resist its rotation.

C⁶ is a feed pendulum free to swing upon a horizontal axis and supported on the bracket C. 65

C⁷ is a feed arm pivotally mounted on the pendulum lever arm and provided with a tooth C⁸ in opposition to the teeth on the tooth ratchet wheel B².

C⁹ is a spring holding said tooth C⁸ in 70 engagement with said wheel.

D is a bracket mounted on the base A.

D¹, D² are horizontally disposed lugs projecting outwardly from said bracket.

D³ is a sleeve pivotally mounted upon said 75 lugs.

D⁴ is a flat spring seat on said sleeve.

D⁵ is a spring on said lugs in opposition to said sleeve D³.

D⁶ is a pendulum lever rigidly mounted 80 on said sleeve D³ perpendicular thereto and located in a horizontal plane and free to swing in said plane as the sleeve rotates.

D⁷ is a pendulum bob on the lever D⁶.

D⁸ is a set screw adapted to lock said 85 pendulum bob in position on the lever D⁶.

D⁹ is a recording lever projecting outwardly from the upper end of said sleeve D³.

D¹⁰ is a stylus carriage pivotally mounted on the end of said lever D⁹ and spring held 90 downwardly against the record sheet on the drum B¹.

D¹¹ is a stylus carried on said stylus carriage and resting upon said record sheet.

D¹² is a dash pot pivotally mounted on 95 the sleeve C⁶ and connected by the link D¹³ with the lever D⁹ to damp its vibration.

It will be evident that, while we have shown in our drawings an operative device, still many changes might be made in size, 100 shape and arrangement of parts without departing materially from the spirit of our invention. We wish, therefore, that our drawings be regarded as in a sense diagrammatic.

The use and operation of our invention 105 are as follows: With our device in position on a train, boat, car or other moving vehicle or moving parts of a moving vehicle the

cover will be locked down on the base to prevent tampering with the device and it will be left alone. When the object upon which it is mounted suffers violent changes in direction the horizontal pendulum will swing forward or back as the case may be and cause the stylus to swing across the record sheet making a mark on the record sheet. The weight of the pendulum bob, its distance from the axis of rotation and the tension of the spring will all be controlled or adjusted to provide for different forces and they will be calibrated against the record sheet so that, for instance, in case the mark goes over a certain distance it indicates a blow of 60,000 foot pounds and for a lesser distance will be 30,000 foot pounds and a lesser distance might be 2,000 or less. It is, of course, obvious that the calibration may be made to suit the convenience of the user.

The dash pot, of course, serves to damp the vibration of the needle on the stylus so that only one swing will be made and the stylus will be immediately returned to neutral position. Simultaneously, however, with the movement of the stylus in response to the horizontal pendulum the vertical pendulum will swing and rotate the ratchet wheel driving the record sheet through an arc subtended by one or two teeth as the case may be, thus feeding the record sheet forward and leaving it ready for a further record. By this arrangement, of course, a record is made only when important changes are to be recorded and the record sheet moves only when important changes are to be recorded. Thus the life of the record sheet is very long as under favorable conditions very few records will be made, and it is not necessary to waste a whole record sheet in an effort to get one or two occasional indications as is the case of records into which the time element enters.

Our device is primarily intended for use on railroad trains and railroad cars, and it is necessary to find out only how often the engineer has started or stopped too suddenly. The time when he did it is of no consequence, since the device is inspected at the end of each trip, and his record will depend only upon the frequency of such indications.

The record sheet is, of course, as indicated in Fig. 7, calibrated in foot pounds and it is only necessary to adjust the pendulum to correspond. The records shown thereon in Fig. 7 are, of course, purely tentative and imaginary but are of such records as would be produced in actual operation.

We claim:

- 60 1. In a recorder a record blank and means for recording thereon changes in velocity and means responsive to said changes in velocity for actuating the record blank.
- 65 2. In a recorder a record blank, means for recording thereon the occurrence of changes

in velocity and their intensity and means responsive to said changes in velocity for actuating the record blank.

3. In a recorder a record blank and means for recording thereon changes in velocity 70 and means responsive to said changes in velocity for actuating the record blank, said means operative in unison.

4. In a recorder a record blank, means for recording thereon the occurrence of changes 75 in velocity and their intensity and means responsive to said changes in velocity for actuating the record blank, said means operative in unison.

5. In a recorder a pendulum free to swing, 80 means for yieldingly resisting its oscillation, means for recording the oscillations of the pendulum, a record blank upon which the record is made and means for actuating said blank, said means comprising a freely swing- 85 ing pendulum.

6. In a recorder a pendulum free to swing, means for yieldingly resisting its oscillation, means for recording the oscillations of the pendulum together with means for measuring the amplitude of said oscillations, a record blank upon which the record is made and means for actuating said blank, said means comprising a freely swinging pendulum. 90

7. A recorder comprising a drum, a record blank wound thereabout, a feed pendulum, means for rotating said drum in response to oscillations of said feed pendulum, a recording pendulum and means for recording oscillations thereof upon said blank. 100

8. A recorder comprising a drum, a record blank wound thereabout, a feed pendulum, means for rotating said drum in response to oscillations of said feed pendulum, a recording pendulum, means for recording oscillations thereof upon said blank and means for recording upon said blank the amplitude of said oscillations. 105

9. A recorder comprising a drum, a record blank wound thereabout, a feed pendulum, means for rotating said drum in response to oscillations of said feed pendulum, a recording pendulum, means for recording oscillations thereof upon said blank and means for recording upon said blank the amplitude of 110 said oscillations, said feed pendulum and said recording pendulum free to oscillate independent one of the other. 115

10. In a recorder a plurality of pendulums 120 one of them a feed pendulum and the other a recording pendulum, one of them free to swing in a vertical plane and the other free to swing in a horizontal plane.

11. In a recorder a feed pendulum free to swing in a vertical plane and a recording pendulum free to swing in a horizontal plane. 125

12. In a recorder a feed pendulum free to swing in a vertical plane and a recording pendulum free to swing in a horizontal 130

plane, said pendulums independent one of the other.

13. In a recorder a feed pendulum free to swing in a vertical plane and a recording pendulum free to swing in a horizontal plane, a recording blank and means for feeding it forward responsive to the oscillations of the feed pendulum.

14. In a recorder a feed pendulum free to swing in a vertical plane and a recording pendulum free to swing in a horizontal plane, said pendulums independent one of the other, a record blank and means for feeding it forward responsive to the oscillations of the feed pendulum.

15. In a recorder a feed pendulum free to swing in a vertical plane and a recording pendulum free to swing in a horizontal plane, a record blank and means for feeding it forward responsive to the oscillations of the feed pendulum, and means for recording the oscillation and the amplitude of the oscillation of the recording pendulum.

16. In a recorder a feed pendulum free to swing in a vertical plane and a recording pendulum free to swing in a horizontal plane, said pendulums independent one of the other, a record blank, means for feeding

it forward responsive to the oscillations of the feed pendulum and means for recording the oscillation and amplitude of the oscillation of the recording pendulum.

17. In a recorder a feed pendulum free to swing in a vertical plane and a recording pendulum free to swing in a horizontal plane, a record blank and means for feeding it forward responsive to the oscillations of the feed pendulum and means for recording the oscillation of the recording pendulum.

18. In a recorder a feed pendulum free to swing in a vertical plane and a recording pendulum free to swing in a horizontal plane, said pendulums independent one of the other, a record blank, means for feeding it forward responsive to the oscillations of the feed pendulum and means for recording the oscillation of the recording pendulum.

Signed at Chicago, Illinois, this 15th day of April, 1913.
